UNITED STATES PATENT OFFICE.

JOHN R. SCOTT, OF OAKLAND, CALIFORNIA.

FARE-REGISTER ATTACHMENT.

No. 867,085.

Specification of Letters Patent.

Patented Sept. 24, 1907.

Application filed December 12, 1906. Serial No. 347,457.

To all whom it may concern:

Be it known that I, JOHN R. SCOTT, a citizen of the United States, residing at Oakland, in the county of Alameda and State of California, have invented new and useful Improvements in Fare-Register Attachments, of which the following is a specification.

My invention relates to an attachment for fare registers, such as are employed in street cars and the like for registering cash fares and transfers.

10 The object of the present invention is to provide a protective device to be attached to the mechanism for operating the fare register and to be actuated in unison therewith, whereby losses to the street car companies by reason of "knocking down" of fares by dishonest employees, may be lessened.

15 The invention comprehends the connection of the fare register mechanism with the electric lighting circuit on the car, whereby the lights will be turned off, or on, according as it is night or day, to indicate to the passengers that the proper fare or fares have been rung up.

Having reference to the accompanying drawings, Figure 1 is an elevation of part of an end of a car showing application of my invention. Fig. 2 is a similar 20 view showing a modification of same. Fig. 3 is a dia-grammatic view of the apparatus represented in Fig. 2.

25 In the embodiment of my invention A represents a car provided with the usual fare register 2, having an operating lever 3; said lever being connected with an arm on the usual rock shaft 5, which latter is provided with projections or arms 6 to be grasped by the conductor.

30 Rocking an arm 6 in one direction, will cause the register lever 3 to record cash fares, and rocking the arm 6 in the opposite direction will cause the same lever to register transfers; all of which is well known in the art.

35 7 is a switch controlling the electric lighting circuit on the car. This switch may be of any appropriate 40 form. In the present instance, for the purpose of adapting this switch to my invention, the switch is shown as a knife-switch, held normally open by means of the spring 8.

45 The switch 7 is connected with the lever 3 by means of a cord or strap 9, so that when the lever 6 is pulled down on in the direction of the arrow to indicate a cash fare on the register 2, the switch is closed momentarily to turn on the lights 10 in the car; my invention being that the actual lighting circuit of the car shall 50 be turned off or on, according as the case may be, each time that a cash fare is rung up, so that every passenger on the car, whether he is in sight of the fare register or not, or whether he can hear the bell or not, will know that a cash fare is being rung up, or will know 55 that it is not being rung up properly.

Although the invention is shown with the switch adapted normally to cut out the lights, it is manifest that the principle is the same, whether the lights are continually lighted or normally extinguished; the two conditions being analogous, and my invention being 60 readily adaptable to either.

By using a flexible cord to connect the switch and lever 3, or by using as here shown a link 9 pivoted to lever 3 and sliding in guides 11 and having an elongated slot or loop in which the switch 7 is engaged, the latter 65 will only be affected to turn off or to turn on the lights when the fare register lever is operated to ring up a cash fare; that is when the lever 6 is pulled down. If a transfer is to be recorded on the fare register, lever 3 is rocked in the opposite direction, but as no motion 70 is imparted to the switch 7 the lighting circuit remains unaffected. This is advisable, because it indicates to the passengers whether a cash fare is paid, or whether a transfer is recorded; it being common practice with dishonest conductors to obtain fraudulent transfers, 75 and when occasion offers to ring up these transfers in lieu of actual cash fares paid. By using my system whereby the lights are turned on for cash fares, and are unaffected for transfers, the opportunities for dishonest practice are materially lessened.

80 In some fare register systems where fares of different denominations are collected; as for example 5c, 10c, 15c, &c., according to the distance of travel, it is common to employ a rockable shaft; said shaft carrying a pointer movable over a dial on which is described 85 fares of different denominations. Before ringing up a fare it is the duty of the conductor to turn this shaft to bring the pointer to the figure or figures which indicate the fare collected, then the fare is rung up on the register in the usual way. My invention is applicable 90 to this system as is shown in Fig. 2-3, wherein 12 represents the rock shaft carrying a pointer 13 movable over conducting plates 14-15-16; said plates having indicated thereon various denominations as 5c-10c and 15c—the fare to be collected. The pointer 13 is electrically conductive, and so are the plates 14-15-16. 95 The pointer and these plates are suitably insulated and are normally out of circuit with one another and the pointer is adapted to be brought successively and the plates to contact therewith to close the circuit 100 between the pointer and the desired plate and thereby to cut in a special lighting circuit. The pointer 13 is shown as being in electrical connection through the wire 17 with the switch 7', which is spring actuated and which is connected with the register lever 3', as 105 previously described. 18 is the opposed member to the knife switch 7', and this member 18 is connected by the wires 19 with one side of the main lighting circuit. The plates 14-15-16 control each a respective 110 lighting circuit, the lights 20 in the circuit which is

controlled by the plate 14 being preferably of one color, as white, the lights 21 which are controlled by the plate 15 being of another color, as red, and the lights 22 controlled by the plate 16 being still of another color, as yellow; these several lighting circuits being connected with the opposite wire 23 of the main lighting circuit.

In operation when the pointer 13 is turned to indicate the 5 cent fare, say as would be shown by plate 14, the 10 pointer and plate 14 are brought into electric contact. When the fare register lever is operated to indicate the fare, the switch 7' is closed and the "white" circuit is lighted up. If the fare should be a 10c fare, and the pointer 13 turned to contact with the plate 15, the red 15 circuit would be lighted, &c; while if the pointer is turned to 24 to indicate transfer, the pointer being out of all electric circuits, no lights will be affected.

It will be manifest that the invention is capable of practice in a variety of forms without departing from 20 the principle herein illustrated.

Having thus described my invention, what I claim and desire to secure by Letters Patent, is

1. The combination in a car, of a fare register having an operating lever, an electric lighting circuit, a switch controlling said circuit, connections between said switch and said lever, and means for operating the lever in two directions, said connections operating in one direction without changing the normal position of the switch and operating in a reverse direction to close the switch and cut-in the light coördinately with the register of a fare. 25

2. The combination of a fare register, means for operating the register, means for indicating fares of different denominations paid, an electric lighting circuit corresponding to fares of different denominations, means for controlling said circuits correspondingly with the denominations of the fares indicated, and means permitting the register to be operated without changing the lighting circuit, when a different character of fare is rung up. 30

In testimony whereof I have hereunto set my hand in presence of two subscribing witnesses.

JOHN R. SCOTT.
